US0D1111986S

(12) **United States Design Patent** (10) Patent No.: **US D1,111,986 S**
(45) Date of Patent: ** Feb. 10, 2026

(54) **CAR FLOOR MAT**

(71) Applicant: **SHANGHAI JUN-DA AUTO DECORATION CO, LTD.**, Shanghai (CN)

(72) Inventor: **Hongjie Ying**, Zhejiang (CN)

(**) Term: **15 Years**

(21) Appl. No.: **29/973,563**

(22) Filed: **Nov. 17, 2024**

(51) **LOC (15) Cl.** **12-16**

(52) **U.S. Cl.**

USPC **D12/203**

(58) **Field of Classification Search**

USPC D12/203, 221; D6/582-586, 592-594

CPC B60N 3/04; B60N 3/044; B60R 13/01

(57) **CLAIM**

The ornamental design for a car floor mat, as shown and described.

DESCRIPTION

FIG. 1 is a front, left and top perspective view of a car floor mat, showing our design.

FIG. 2 is a rear, right and bottom perspective view thereof.

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the car floor mat, which form no part of the claimed design.

1 Claim, 8 Drawing Sheets
